(57) **CLAIM**

The ornamental design for a faucet drip catcher, as shown and described.

DESCRIPTION

FIG. 1 is a front perspective view of a faucet drip catcher showing my new design;

FIG. 2 is a rear perspective view thereof;

FIG. 3 is a front elevational view thereof;

FIG. 4 is a rear elevational view thereof;

FIG. 5 is a left side view thereof, and the right side view being a mirror image of FIG. 5;

FIG. 6 is a top plan view thereof;

FIG. 7 is a bottom plan view thereof;

FIG. 8 is an enlarged detail view of area 8 of FIG. 1;

FIG. 9 is an enlarged detail view of area 9 of FIG. 1;

FIG. 10 is an enlarged detail view of area 10 of FIG. 1;

FIG. 11 is an enlarged detail view of area 11 of FIG. 2;

FIG. 12 is an enlarged detail view of area 12 of FIG. 2;

FIG. 13 is an enlarged detail view of area 13 of FIG. 2;

FIG. 14 is an enlarged detail view of area 14 of FIG. 3;

FIG. 15 is an enlarged detail view of area 15 of FIG. 3;

FIG. 16 is an enlarged detail view of area 16 of FIG. 3;

FIG. 17 is an enlarged detail view of area 17 of FIG. 4;

FIG. 18 is an enlarged detail view of area 18 of FIG. 4;

FIG. 19 is an enlarged detail view of area 19 of FIG. 4;

FIG. 20 is an enlarged detail view of area 20 of FIG. 5;

FIG. 21 is an enlarged detail view of area 21 of FIG. 5;

FIG. 22 is an enlarged detail view of area 22 of FIG. 6;

FIG. 23 is an enlarged detail view of area 23 of FIG. 7; and,

FIG. 24 is an enlarged detail view of area 24 of FIG. 7.

The broken lines in the figures depict portions of the faucet drip catcher, that form no part of the claimed design. The dot dash broken lines indicate cutoff boundaries for enlarged detailed portion views and form no part of the claim.

1 Claim, 15 Drawing Sheets
